UNITED STATES PATENT OFFICE

BLOOMFIELD H. HOWARD, OF WASHINGTON, DISTRICT OF COLUMBIA

FEEDER FOR INGOT MOLDS

Application filed June 18, 1929. Serial No. 371,776.

My invention relates to improvements in feeders for ingot molds.

The present invention relates broadly to the art of metal founding and more particularly to an improved means for feeding the shrinkage caused by solidification or cooling of relatively large bodies of metal such as ingots and is an improvement on my application for Improvements in feeders for ingot molds, filed December 12, 1927, Serial No. 239,494.

The present invention has for one of its objects, the provision of a feeder adapted to cooperate with the upper end of the ingot mold and so constructed as to contain a maximum of liquid metal under such conditions that the effective area of the ingot mold is not substantially reduced and in such manner that the minimum reduction of heat with a maximum head of molten metal is available at all times.

The invention contemplates the utilization of a feeder having the maximum cross sectional area at its lower end and exterior therefrom, with an upwardly and inwardly curved wall portion terminating at its upper end into a relatively restricted opening of substantial contour communicating at its upper end directly to the atmosphere.

The invention further contemplates the provision of such reserved body of metal preferably entirely above the plane of the top edge of the mold to thereby preserve the maximum capacity of the mold and give the desired head. It further contemplates that the utilization of the interior walls of such contour that the radiation of heat from the molten metal combined thereby, is reduced to a minimum, radiation being restricted by the reflection back upon the molten metal of heat rays emanating therefrom.

Another object of the invention is to provide feeders of this character in which the curved walls are provided with large numbers of radiating faces to radiate the heat back upon the molten metal and of a contour whereby the molten metal will not strongly adhere thereto, but allow the more ready feeding of the molten metal to the ingot as it solidifies. The use of curved walls of

many surfaces is of particular advantage in that a decrease in the level of the molten metal within the feeder increases the rapid pulling away of such metal from the curved walls, or in other words, provides areas of rapidly increasing cross section for the reception of metal as it moves downwardly. In this manner the tendency of the metal to adhere to the inner wall of the feeders is reduced and the entire body of metal is effective for forcing a supply of molten metal into the body of the ingot to feed shrinkage.

Another object of the invention is to provide a relatively small opening to feed the molten metal therethrough and effectively minimize heat radiation of the molten metal within the feeder. The substantially straight cylindrical wall portions forming the opening to the atmosphere provide a sufficient body of feeder material to effectively resist cracking or spilling with the consequent disadvantage caused by the presence of refractory material within the body of the ingot.

In the accompanying drawings:—

Figure 1 is a prospective view of a feeder applied to a mold and embodying this invention.

Figure 2 is a vertical sectional view of Figure 1.

Figure 3 is a vertical sectional view of a slightly modified form of feeder.

Figure 4 is a top plane view showing a modified form of the multiple heat reflecting walls.

Figure 5 is a vertical sectional view of a further modified form of feeder.

Figure 6 is a sectional view similar to Figure 5 showing the multiple heat reflecting walls extending to the lower end of the feeder.

Figure 7 is a vertical sectional view of a still further modified form of feeder.

Figure 8 is a vertical sectional view similar to Figure 7 showing the multiple heat reflecting walls extending to the lower end of the feeder.

In the accompanying drawings:—

1 represents the mold and 2 the feeder which is preferably of a cylindrical form.

adapted to fit within the bore of the mold and having the outwardly supporting ribs or ears 3 arranged on all the sides for supporting the feeder within the upper end of the mold. The feeder which is provided with a bore and through the maximum diameter of which is at the lower end of the feeder and the interior walls of said bore are curved upwardly and inwardly from said maximum 5 diameter or cross sectional area to the minimum diameter or cross sectional area, terminating into the restricted filling opening 4 at the extreme upper end of the feeder. The walls 5 of the bore of the feeder are serrated 10 or corrugated, said serrations or corrugations extending from the top to the bottom of the feeder forming an opening through the feeder having numerous narrow faces whereby the heat is more effectively reflected back 15 upon the molten metal and also preventing the metal of the ingot from strongly adhering thereto, to allow the free shrinkage of the ingot as it gradually solidifies. In Figures 1 and 2, I have shown serrations while 20 in Figure 4 I have shown the bore of the feeder having corrugations 6.

In the modifications shown in Figure 3 of the drawings the feeder is constructed the same as shown in Figures 1 and 2 on its exterior, but the bore 8 of the feeder has its 30 maximum diameter starting from the lower end of the feeder and its minimum diameter or cross sectional area at the point 9 below the upper end of the feeder and terminating in a vertical opening 10 of the same diameter as the minimum diameter or cross sectional area of the feeder. The walls of the opening 35 10 are preferably smooth and through this opening the molten metal is poured.

In the modification shown in Figure 5 of the drawings I have shown the feeder 11 having the bore 12 of the same diameter from the lower end 13 to the point 14 and from the point 14 upwardly and is curved inwardly 40 and provided with the serrations or corrugations 15 which terminate at 16. The minimum diameter or cross sectional area of the bore of the feeder has extending therefrom the small opening 17, having smooth vertical 45 walls. The body of the feeder as shown in Figure 5 has its exterior surface at its upper end corresponding to the curve of the bore of the feeder.

In the modification shown in Figure 6 I 50 have shown the feeder 18 constructed on the exterior exactly the same as shown in Figure 5. In this figure I have shown the corrugations or serrations 19 starting at the extreme lower end of the feeder its maximum cross 55 sectional area and terminating at 20. The minimum diameter or cross sectional area communicating with the cylindrical filling or pouring opening 21 having smooth walls.

In the modification shown in Figure 7 the 60 exterior contour of the feeder 22 is the same

as that shown in Figures 1 and 2 of the drawings, and the bore 23 of the feeder has its maximum diameter or cross sectional area extending from the lower end to the point 24 and from the point 24 the walls converge inwardly in a straight line indicated at 25 and terminating at 26. The minimum diameter or cross sectional area communicates with the filling or pouring opening 27 having smooth walls. The oblique walls 25 having corrugations or serrations 28 which extend from the maximum diameter or cross sectional area to the minimum diameter or cross sectional area. 70 75

The modification shown in Figure 8, the feeder 29 is of the same construction as that shown in Figure 7, but has the corrugations 30 extending from the lower end of the feeder upwardly throughout the maximum diameter or cross sectional area to the minimum cross sectional area or diameter to the opening 31. 80 85

Having thus fully described my invention, what I claim is:—

1. A feeder for ingot molds comprising a heat retaining body portion adapted to cooperate with the upper end of a mold and having its interior walls provided with many reflecting faces extending upwardly and curved inwardly and terminating in an opening. 90 95

2. A feeder for ingot molds comprising a heat retaining body adapted to cooperate with the upper end of the mold having a portion of minimum cross sectional area, and a portion of maximum cross sectional area connected by an upwardly and inwardly extending wall having many faces. 100

3. A feeder for ingot molds comprising a heat retaining body adapted to cooperate with the upper end of the mold and comprising a portion of minimum cross sectional area and a portion of maximum cross sectional area with an upwardly and inwardly curved wall portion of many faces extending between and defining said areas, and with a relatively restricted opening communicating at its lower end to the portion of minimum area. 105 110

4. A feeder for ingot molds comprising a heat retaining body adapted to cooperate with the upper end of a mold, and defining a metal containing opening of minimum cross sectional area gradually merging into a portion of maximum cross sectional area and defined by an upwardly and inwardly curved wall of many faces, said feeder having an opening of relatively small diameter at its upper end with substantially straight walls of substantially cylindrical contour, the cross sectional area of said feeder permitting unrestricted downward movement of all metal therein. 115 120 125

5. A feeder for ingot molds comprising a heat retaining body adapted to be supported by the upper end of the ingot mold, said member having an area of minimum diameter in a plane a substantial distance above the up- 130

per end of the ingot mold, and the area of maximum diameter in a plane adjacent the upper end of the ingot mould and having upwardly and inwardly directed walls of 5 many faces intermediate said area, and having an opening of relatively small diameter at its upper end adapted to minimize the radiation of heat therethrough.

6. In a hot top, a hollow body having a restricted opening at the top and having a heat deflecting wall portion of many faces of relatively large area extending from said opening to the main body portion thereof.

7. In a hot top, a hollow body having a restricted opening at the top and having a heat deflecting wall portion of many faces extending from said opening to substantially the mid-portion thereof.

In testimony whereof, I have signed this
20 specification.
